UNITED STATES PATENT OFFICE.

ALFRED M. HEWLETT, OF KEWANEE, ILLINOIS.

METHOD OF MOLDING.

No. 808,368.

Specification of Letters Patent.

Patented Dec. 26, 1905.

Application filed January 16, 1904. Serial No. 189,390.

To all whom it may concern:-

Be it known that I, ALFRED M. HEWLETT, a citizen of the United States, residing at Kewanee, in the county of Henry and State of Illinois, have invented a certain new and useful Method of Molding, of which the following is a specification, reference being had to the accompanying drawings.

My invention relates to the molding of sand or analogous material, either for the formation of cores or in making molds, and it should be understood that the term "mold," as hereinafter employed, is intended to include not only a box for making cores, but also a flask for making molds in which to make castings, and also that the term "molding," as hereinafter employed, is used in a like generic sense.

Heretofore various attempts have been made to make sand-molds by the use of compressed air or equivalent gas; but, so far as I am aware, none of such efforts have been successful from a practical standpoint. According to one of such prior processes the molds have been first filled with sand and afterward subjected to the action of compressed air for the purpose of packing the sand in the mold. Again, it has been proposed to sift or shower the sand into the mold through an air-tight compartment into which compressed air is admitted, the idea being that the air would pack the sand in the mold. A still further method proposed was to employ compressed air to drive a follower placed upon a mass of sand for the purpose of driving the sand into the mold, in such case the compressed air being employed as a substitute for a piston. As above suggested, however, none of the processes above outlined have been successful, and, so far as I am aware, prior to my present invention compressed air or equivalent gas has never been successfully employed for molding sand or equivalent substance. I have discovered, however, that if compressed air be applied directly to sand supported in mass adjacent to the mold in such manner that the expansive force of the compressed air may serve to carry the sand into and distribute it throughout the mold it may be employed with the greatest success for molding sand and analogous substances, and this constitutes the generic feature of my present invention.

In carrying out my present invention the sand is supported in mass in a suitable chamber adapted to contain compressed air, and

the mold to be filled is brought into communication with said chamber, so that the sand under the action of the compressed air is free to pass from the compression-chamber into and throughout the mold. The connection between the mold and the compression-chamber is made practically air-tight; but the mold itself is supported in such manner as to permit of the escape of the air after it has done its work. Compressed air is then admitted to the compression-chamber above the sand, which it instantly penetrates, the sand nearest the mold being carried by the expansive force of the compressed air into and throughout the mold, which is at once filled with a homogeneously-packed mass of sand. What may be termed the "exhaust-air"—that is to say, the air that passes into the mold—escapes therethrough and leaves the sand packed therein. The compression-chamber is then exhausted in any convenient way, so that the sand remaining therein is relieved from pressure, when the mold may be separated from the compression-chamber and replaced by a fresh one.

In the joint applications of Maddra J. Hewlett and myself, Serial No. 177,353, filed October 16, 1903, and Serial No. 180,498, filed November 9, 1903, are fully described molding-machines designed to carry out my improved process; but in the accompanying drawings I have illustrated a simpler form of machine constructed along the same lines as that of the application Serial No. 177,353, above mentioned, which will suffice for a clear understanding of the method herein claimed.

Referring to the drawings, Figure 1 is a side elevation of a rotary molding apparatus designed to carry out my said invention. Fig. 2 is a vertical section thereof. Fig. 3 is an end view. Fig. 4 is a sectional view of the valve for controlling the admission and escape of compressed air to the compression-chamber. Fig. 5 is a view of the upper portion of the compression-chamber. Fig. 6 is a sectional view of the connections by which compressed air is supplied to the compression-chamber; and Figs. 7 and 8 are side and plan views, respectively, of automatic mechanism for exhausting the compressed air from the compression-chamber and supplying it thereto.

In the accompanying drawings, 9 indicates the base-plate of the machine, and 10 the top plate thereof. The base-plate is preferably circular in form and the top plate ellip-

tical; but they may be made of any suitable shape. Said plates are rigidly secured together by standards 11 12, which are preferably tubular.

- 5 13 indicates a shaft centrally disposed which is supported at its lower end in a bearing-block 14, secured to the base-plate 9, its upper end being secured in the top plate 10, as shown.
- 10 15 indicates a boss which forms a bearing for the upper end of the shaft 13.
- 16 indicates a disk or supporting-plate mounted on the shaft 13, near the upper end thereof, and carrying one or more compression-chambers 17 18, which depend therefrom, as shown in Fig. 1. The construction of said compression-chambers is best shown in Figs. 2 and 3, from which it will be seen that they are slightly tapered, being larger at the bottom than at the top, their lower portions being elliptical in cross-section.
- 19 indicates perforated plates which partly close the lower ends of the compression-chambers 17 18, providing one or more contracted passages through which compressed air charged with sand is admitted to the mold.
- 20 indicates a cup which is carried at the lower end of a rod 21, fitted in the top plate 10, and is adapted to fit upon the upper ends of the compression-chambers 17 18 when they are in proper position to receive it.
- As best shown in Figs. 2 and 6, at its lower end the cup 20 is provided with an annular flange 22, which is adapted to fit upon a gasket 23, of rubber or other suitable material, to form an air-tight connection between said cup and the compression-chamber. The rod 21 is vertically movable to raise and lower the cup 20, thereby moving it into and out of operative position.
- 24 indicates an air-passage in the cup 20 which extends from the lower surface of the cup to an air-pipe 25. (Shown in Fig. 6.)
- 45 Said air-pipe communicates with a valve 26, by which the admission and exhaustion of air from the compression-chamber is controlled. Said valve consists of a valve-chamber 27, which contains a slide-valve 28, and is provided with passages 29 30. The passages 29 30 lie adjacent to each other and are normally cut off from the valve-chamber 27 and placed in communication with each other by the slide-valve 28, which, as shown in Fig. 4, overlies the inner ends of said passages and is provided with a concavity 31, which affords communication between them. By moving said slide-valve longitudinally in the direction indicated by the arrow in Fig. 4 it moves from over the passage 29, thereby opening communication between said passage and the valve-chamber 27, the passage 30, however, being still cut off from said valve-chamber. The passage 30 communicates with an exhaust-pipe 32, while the

valve-chamber receives compressed air through a supply-pipe 33, as shown in Fig. 4. By the construction described when the slide-valve 28 is in the position shown in Fig. 4 the pipe 25 is connected with the exhaust-pipe 32 through passage 29, concavity 31, and passage 30. When, however, the slide-valve 28 is moved in the direction indicated by the arrow in Fig. 4, the passage 29 is connected with the valve-chamber 27 and receives compressed air therefrom, thereby admitting compressed air to the compression-chamber 18.

The slide-valve 28 is automatically operated to control the admission of compressed air to the compression-chamber and its exhaustion therethrough by means of a lever 34, pivoted upon a standard 35, supported on the top plate 10, as shown in Fig. 1. At its outer end the lever 34 is provided with a finger 36, which is adapted to be engaged by the projecting portion 37 of a cam 38, mounted on a shaft 39, as best shown in Figs. 1 and 7, the arrangement being such that as said cam rotates in the direction indicated by the arrow in Fig. 7 it depresses the outer end of the lever 34, thereby throwing the inner end of said lever upward. As shown in Figs. 1 and 4, the inner end of said lever is connected by a connecting-rod 40 with the slide-valve 28. It follows that when the cam 38 acts upon the lever 34 the slide-valve 28 is moved into position to supply air to the cup 20 and through it to the compression-cylinder. The lever 34 is restored to its normal position when the projecting portion 37 passes the finger 36 by a spring 41, connected to the inner end of said lever and to the top plate 10, as shown in Fig. 1.

The cup 20 is operated to connect the compression-chambers in turn with the compressed-air supply by means of an eccentric 42, mounted on the shaft 39, as shown in Figs. 1 and 2. Said eccentric is connected by an eccentric-strap 43 and arm 44 with a lever 45, the middle portion of which is connected by a pivot 46 with a head 47 at the upper end of a rod 48, which extends down at one side of the machine, having a suitable bearing in the top plate 10 and in a bracket 49, supported by the standard 11, as shown in Fig. 2. At its lower end the rod 48 carries a bracket 50, in which is adjustably secured a pin 51. The pin 51 is vertically disposed in such position as to register with a boss 52, which projects downwardly from a mold-supporting plate 53, carried by a turn-table 54, mounted on the shaft 13 near the lower end thereof, as shown in Fig. 2. A mold-supporting plate 53 is provided for each compression-chamber, and they are so mounted on the turn-table 54 as to support their respective molds immediately under the plates 19, as shown in Fig. 2.

55 indicates the molds, carried by the sup-

porting plates 53, and 56 57 stops which control the position of the molds on the mold-supporting plates 53.

The turn-table 54 is so mounted upon the shaft 13 as to be vertically adjustable, its height being adjusted relatively to the length of the molds, so that when the mold-supporting plates 53 rest upon the turn-table the upper ends of the molds are a short distance removed from the lower surface of the plates 19. When, however, the plates 53 are raised, as will be hereinafter described, the molds are brought into close contact with the plates 19, so that sand from the compression-chambers 15 may readily pass into the molds under the action of the compressed air. The plates 53 are raised when they lie over the pins 51 by the action of the eccentric 42, which rocks the lever 45 and raises and lowers the rod 48 20 with the pin 51. When the pin 51 is raised, it engages the boss 52 and raises the plate 53 to carry the mold 55 into contact with the plate 19, as above described. The air-cup 20 is depressed at the same time that the plate 53 25 is raised by means of the rod 21, which is connected to the inner end of the lever 45 by a pivot 58, as shown in Fig. 2, and consequently descends when the rod 48 rises. By this 30 means an air-tight closure of the upper end of the compression-chamber is effected at the same time that the mold is brought into operative relation to the lower end thereof, so that when compressed air is admitted to the compression-chamber in the manner hereinbefore described sand from the compression-chamber 35 is carried into and throughout the mold and packed therein. The surplus or exhaust air escapes around the edges of the mold, as the contact between the mold and its support is not air-tight. When desired, 40 special means may be provided for the escape of the exhaust-air.

The eccentric-shaft 39 is driven from a drive-shaft 59, which is connected to the shaft 45 39 through gears 60 61, as shown in Fig. 3. The drive-shaft 59 may be driven from any suitable source of power and is preferably provided with fast and loose pulleys 62 63, respectively.

50 64 indicates a hopper through which sand is supplied to the compression-chambers 17 18, said hopper having an extension 65, extending down from the top plate 10 to the disk 16, as shown in Fig. 2.

55 66 indicates an endless carrier for supplying sand to the hopper 64.

In operation the mass of sand is supported in the compression-chambers 17 18 upon their respective plates 19, which may be provided with any suitable number of perforations. The molds are carried on the turn-table 54, one being provided for each compression-chamber, and as both the turn-table 54 and the disk 16 are connected to the same 65 shaft they rotate in unison. The shaft may

of course be intermittently rotated in any suitable manner. When any compression-chamber arrives under the air-cup 20, the eccentric 42 is operated to rock the lever 45, thereby depressing the cup 20 into engagement with the upper end of the compression-chamber and raising the mold into engagement with the plate 19. The air-valve is then operated to admit compressed air to the compression-chamber above the mass of sand 75 therein. Immediately upon its admission into the compression-chamber the air permeates the mass of sand and by its expansive force carries the sand at the bottom of the mass into and throughout the mold, packing 80 it therein and ultimately escaping through the cracks or apertures provided for that purpose. The valve is immediately afterward operated to exhaust the compressed air from the compression-chamber, after which the 85 cup 20 is raised and the pin 51 lowered, permitting the mold to descend out of engagement with the compression-chamber, when it may be removed, a fresh one being put in its place. 90

The foregoing description of the apparatus illustrated will suffice to convey a clear understanding of my improved method, and it will be understood that while such apparatus may be satisfactorily employed to carry out 95 said method many features may be added thereto for the purpose of making the operation automatic, as illustrated in the machine described in my former application, Serial No. 177,353. Various other forms of apparatus 100 may also be employed in carrying out said process, and I wish it to be understood that my invention is not restricted to the use of any special apparatus, neither is it restricted 105 to the use of compressed air, as any other equivalent gas suitable for the purpose may be employed.

So far as I am aware I am the first in the art to successfully employ the expansive force of compressed air for carrying particles 110 of sand into and distributing them throughout the mold, and therefore my invention is a pioneer one, and the claims hereinafter made are to be construed accordingly.

That which I claim as my invention, and 115 desire to secure by Letters Patent, is—

1. The method of molding which consists in applying compressed air directly to a mass of sand supported in communication with an empty mold placed so that the expansive force of the air carries small particles or grains from said mass and distributes and 120 packs the same into and throughout the mold, substantially as described.

2. The method of molding which consists 125 in supporting the sand in mass in a suitable receptacle, making a substantially air-tight connection between the interior of said receptacle and an empty mold, and then admitting compressed air directly to the mass of sand 130

in said receptacle to distribute and pack the sand into and throughout the mold by its expansive force, substantially as described.

3. The method of molding which consists in supporting the sand in mass in a suitable receptacle having a partly-open support for said mass of sand, making a substantially air-tight connection between the interior of said receptacle and an empty mold, then admitting compressed air directly to the mass of sand in said receptacle and distributing and packing the sand into and throughout the said mold by the expansive force of the air, substantially as described.

15 4. The method of molding which consists in supplying compressed air directly to a mass of sand supported adjacent to and in communication with the mold and directing the grains of sand propelled by the expansive force of the compressed air into and throughout the mold, substantially as described.

5. The method of molding which consists in supporting the sand in mass in a suitable receptacle adjacent to and above the mold, 25 forming a substantially air-tight connection between the interior of the sand-receptacle and the mold, and then admitting compressed air directly to the mass of sand in said receptacle to force the particles comprising the same into and throughout the mold, substantially as described.

6. The method of molding which consists in supplying sand in mass to a suitable receptacle adjacent to and above the mold, forming a substantially air-tight connection between the interior of the sand-receptacle and the mold, the latter being arranged to permit the escape of air after its passage therethrough, and then causing compressed air to 35 pass through the sand-receptacle, and carry particles of sand with it through the connection and the mold, substantially as described.

7. The method of molding which consists in supporting the sand in mass in a suitable 45 receptacle adjacent to and above the mold, forming a substantially air-tight connection between the interior of the sand-receptacle and the mold, then admitting compressed air directly to the mass of sand in said receptacle 50 to force the particles thereof into and throughout the mold, then exhausting the compressed air remaining in said receptacle, and then removing the mold, substantially as described.

8. The method of molding which consists in introducing compressed air charged with sand through a contracted passage into a mold, and permitting the air to expand in the mold and distribute the sand therein by its expansive force.

9. The method of molding which consists in placing a mold in communication with a suitable receptacle containing sand in mass, and then admitting air under pressure into said receptacle above and throughout the 65 mass of sand.

10. The method of molding which consists in placing a mold in communication with a suitable receptacle containing sand in mass, then establishing pneumatic pressure in said receptacle above and throughout the mass of sand, and then reducing the pressure in said receptacle and removing the mold.

11. The method of molding which consists in placing a mold in communication through 75 a contracted passage with a suitable receptacle containing sand in mass, then admitting air under pressure into said receptacle above and throughout the mass of sand, thereby forcing sand through said contracted passage 80 into the mold and distributing it therein by the expansive power of the air, and then cutting off the air-pressure.

12. The method of molding which consists in placing a mold in communication with a 85 suitable receptacle containing sand in mass, and then causing compressed air to penetrate the mass and carry particles of sand from that portion of the mass lying next to the mold, into and throughout the mold.

13. The method of making sand-molds which consists in carrying the sand into the mold and packing it therein by means of the expansive force of compressed air.

14. The method of molding, which consists 95 in supporting the sand in mass in a suitable receptacle having a partly-open bottom, placing said bottom directly on the mold, then admitting air into said receptacle until the pressure of air is sufficient to force the 100 sand in said receptacle out through the partly-open bottom and distribute and pack it uniformly throughout the mold.
